[57] CLAIM

The ornamental design for a tape dispenser, as shown and described.

DESCRIPTION

FIG. 1 is a top, left, front isometric view of a first embodiment of a tape dispenser showing our new design;

FIG. 2 is a left side elevational view of the tape dispenser illustrated in FIG. 1;

FIG. 3 is a right side elevational view of the tape dispenser illustrated in FIG. 1;

FIG. 4 is a top plan view of the tape dispenser illustrated in FIG. 1;

FIG. 5 is a bottom plan view of the tape dispenser illustrated in FIG. 1;

FIG. 6 is a front elevational view of the tape dispenser illustrated in FIG. 1;

FIG. 7 is a rear elevational view of the tape dispenser illustrated in FIG. 1;

FIG. 8 is a top, left, front isometric view of a second embodiment of a tape dispenser showing our new design;

FIG. 9 is a left side elevational view of the tape dispenser illustrated in FIG. 8;

FIG. 10 is a right side elevational view of the tape dispenser illustrated in FIG. 8;

FIG. 11 is a top plan view of the tape dispenser illustrated in FIG. 8;

FIG. 12 is a bottom plan view of the tape dispenser illustrated in FIG. 8;

FIG. 13 is a front elevational view of the tape dispenser illustrated in FIG. 8;

FIG. 14 is a rear elevational view of the tape dispenser illustrated in FIG. 8;

FIG. 15 is a top, left, front isometric view of a third embodiment of a tape dispenser showing our new design;

FIG. 16 is a left side elevational view of the tape dispenser illustrated in FIG. 13;

FIG. 17 is a right side elevational view of the tape dispenser illustrated in FIG. 13;

FIG. 18 is a top plan view of the tape dispenser illustrated in FIG. 16;

FIG. 19 is a bottom plan view of the tape dispenser illustrated in FIG. 16;

FIG. 20 is a front elevational view of the tape dispenser illustrated in FIG. 16;

FIG. 21 is a rear elevational view of the tape dispenser illustrated in FIG. 16;

FIG. 22 is a top, left, front isometric view of a forth embodiment of a tape dispenser showing our new design;

FIG. 23 is a left side elevational view of the tape dispenser illustrated in FIG. 22;

FIG. 24 is a right side elevational view of the tape dispenser illustrated in FIG. 22;

FIG. 25 is a top plan view of the tape dispenser illustrated in FIG. 22;

FIG. 26 is a bottom plan view of the tape dispenser illustrated in FIG. 22;

FIG. 27 is a front elevational view of the tape dispenser illustrated in FIG. 22; and,

FIG. 28 is a rear elevational view of the tape dispenser illustrated in FIG. 22.
